UNITED STATES PATENT OFFICE

LE ROY J. LEISHMAN, OF LOS ANGELES, CALIFORNIA

TELEGRAPHOPHONE

Application filed October 6, 1927. Serial No. 224,468.

This invention relates to electrical reproducers and has for its principal object the provision of a simple and efficient device which can be attached to an ordinary phonograph, either permanently or readily detachably, in place of the usual reproducer and may be electrically connected to a radio set without in any way affecting the use of the radio set in its usual receiving of radio signals.

A further object of the present invention is the provision of a reproducer unit particularly suited to reproducing phonograph selections by radio amplification.

A still further object of the invention is the provision of an electric circuit whereby one of the pick-up leads is inserted between the grid leak and the detector tube whereby the detector tube may be utilized as an amplifier tube, the grid leak and condenser being substantially eliminated from the circuit electrically without in any way interfering with their function in the ordinary use of the device for radio reception.

A still further object of the present invention contemplates the use of a jack in the radio set thru which by a suitable plug the reproducer or pick-up may be electrically connected to the amplifying portion of the radio set, automatically disconnecting the plate of the detector tube from the primary of the first audio tube.

While it is a very simple matter to design a radio receiver so that the grooves in a phonograph disk will operate to produce changes of electric current which may readily be amplified in ordinary fashion, devices of this kind have never gone into wide commercial use because of the trouble and nuisance in making the connections or because of the quite unnecessary expense of having a separate and distinct audio set for the phonograph which obviously would scarcely ever be used at the same time that radio music is being received.

In the drawings:—

Figure 1 shows a simple embodiment of the invention.

Figure 2 shows a modified form of connection.

Figure 3 shows a circuit in which the pick-

up or reproducer may be plugged into the radio circuit which is automatically reconnected for radio reception when the plug is withdrawn.

Figure 4 shows a modification.

The pick-up has a casing 10, preferably of a phenol condensation product, which is a cup-shaped shell having an integral tubular extension 11 lined with a soft rubber ring readily and snugly fitting upon the tone arm of a phonograph. While I much prefer that this casing be readily detachable it may obviously be permanently secured to the tone arm and the latter may or may not be readily detachable. Within the casing is a reproducer unit including a coil 15, the terminals of which are connected to binding posts 16 and 17 which receive the tips of the connecting cord 18 which passes thru a hole such as 19 in the rear of the casing.

The spool 15 is secured between channel pieces 22 and 23 which are secured to the pole pieces 20 and 21 of a permanent magnet. The channel 23 is riveted or otherwise secured to the face plate 25 and supports the magnet 75 and coil. The screw 24 holds the binding posts 16 and 17 in place on the face plate.

The armature 26 is a flat piece of soft iron pivoted centrally of the coil 15 and urged to one side by the gum rubber damper 28. The front plate 25 which carries the magnet, the coil and all parts within the casing 10, is secured to the casing by screws such as 30 which also hold in place the light metal guard 32 shielding the vibrating lever 35 which rests against a damping soft rubber disk 37. The lever 35 is connected to the armature 26 by a light arm 38, the two rubber dampers 37 and 28 acting, as will be noted, on opposite sides of the disk and substantially neutralizing each other as far as moving the armature is concerned but acting additively, in damping. The vibrating lever 35 is pivoted to the face plate 25 preferably by pressing the bracket 38, to which is permanently secured both the lever 35 and the needle carrier 40, against the knife edge lugs 41 of the face plate by means of springs 42, the tension of which may be adjusted by means of the screws 44. I find it highly

advantageous to insert damping bits of soft rubber 45 under each end of each spring.

The cord 18 from the binding posts 16 and 17 leads to the radio set, a very convenient method of attachment being as shown in Figure 4, one wire of cord 18 such as 50 connecting into the radio circuit between the grid and the grid leak and the other wire such as 51 being connected to the "A" battery, 10 preferably on the negative side for in this way the detector tube acts to amplify the current from the pick-up. A convenient method of making the connection is shown in Figure 1, 53 being the grid condenser, 54 the 15 grid leak and 55 the spring clip which supports the grid leak when one of the type shown is used. The wire 50, having a switch 56 therein, leads to a metal cone 57 which fits on the end of the grid leak 54. In the 20 actual construction it is preferable to have an extra U-shape terminal such as 58 which is used when the set does not have the elongated tubular grid leak such as 54 but uses a variable leak. The wire 51 also has a regulation 25 U-shaped terminal 59 which may be connected directly to the "A" battery. Between the cord 18 and the wires 50 and 51 I provide a small case 60 containing a bypass condenser 61 of approximately one microfarad and a variable resistance 62 of 30 about seventy-five kilohms. This case is a standard unit and is not essential in most cases since no blocking condenser is needed in the hook-up of Figure 1 but is needed in 35 case the reproducer is connected to the plate terminal of the detector tube instead of to the grid terminal as preferred.

A very simple form of connection includes the use of a disk 70 (Figure 2) containing 40 four holes to receive the prongs of a standard UX tube. In one of the holes for the filament terminals such as the one receiving the prong 71 and either the plate or the grid hole, are placed contacts 73 which touch 45 the tube prongs and the wires 50 and 51 are connected to these contacts. The device is very similar to the ordinary adaptor, particularly those with power tube connections and external leads. This disk 70 slips on 50 the base of the detector tube and leads are sufficiently small and flexible to fit easily between the tube and the old-fashioned socket should the latter be used.

Referring now particularly to Figure 3, 55 80 is the detector tube and 82 is the primary winding of the first audio transformer which is connected to the outside terminals 83 and 84 of a jack, the inside terminals 85 and 86 being connected respectively to the plate of 60 the detector and to the positive side of the detector "B" battery. When the plug is not in the jack the device acts as a straight radio receiver, the detector plate being connected to the plus side of the "B" battery providing 65 the proper voltage for the detector tube,

thru the primary winding of the first audio in the usual fashion. In this hook-up the two wires 88 from the pick-up lead to a modulator plug 89 which is a standard article of commerce and intended generally to control the volume of loud speakers and contains a variable resistance controlled by a knob 90. 70

By inserting the plug 89 in the jack the reproducer is connected into the amplifying portion of the radio set and the detector tube is disconnected by the breaking of the current between the contacts 83 and 85. This hook-up is very similar in effect to that had by providing a prong carrying member readily insertable into the detector tube socket to engage a filament and the plate spring contacts, but is much neater in looks and is very much less trouble particularly since in all old style sets the jack described is already in place in the set and is intended for the reception of the head piece plug except that the connections are reversed. In transforming an old-fashioned set nothing whatsoever need be done save the changing of the jack terminals, that is, connecting the first audio 80 to the outside terminals instead of to the inside as the sets are ordinarily wired. 85

In Figure 4 I have shown the hook-up used in Figure 1 or in connection with the disk 70 of Figure 2. The detector tube is 80, the primary of the first audio is 82, the grid leak is 54, the grid condenser is 53. One prong of the jack 91 is connected to the side of the grid leak nearest the tube as more clearly shown in Figure 1 and the other terminal is connected to the lead from the negative side 93 of the "A" battery. The wires 50 and 51 are connected to a plug 95 which when inserted in the jack 91 connects the reproducer as indicated. In this hook-up I have again 100 shown my standard case 60 with the condenser and variable resistance but obviously the reproducer may be hooked to the plug of a standard modulator as shown in Figure 3. 105 The condenser 61 is not objectionable however, and is quite essential where the connection is made to the plate of the detector instead of to the grid. 110

What I claim is:

1. A connecting means for electrically connecting a telegraphophone sound box with a radio receiver consisting of a metal cone adapted to be inserted between a conical ended grid leak and its holder. 115

2. A connecting means for electrically connecting a telegraphophone sound box with a radio receiver, said means including a terminal held in place between the grid leak and its holding device which terminal is not removed when the radio receiver is used for its normal function of receiving radio signals. 120

In testimony whereof I affix my signature.

LE ROY J. LEISHMAN.
